(57) **CLAIM**

The ornamental design for a boxing machine, as shown and described.

DESCRIPTION

FIG. 1 is a front perspective view of a boxing machine, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof; and,

FIG. 10 is an enlarged detail view of area 10 in FIG. 2.

The broken lines in the drawings illustrate the portions of the boxing machine, which form no part of the claimed design. In the drawings, the dash-dot-dash broken lines indicate boundaries of the enlarged views and form no part of the claimed design.
